A. B. EDMANDS, OF MELROSE, MASSACHUSETTS.

Letters Patent No. 80,714, dated August 4, 1868.

IMPROVEMENT IN WATER-METERS.

The Schedule referred to in these Letters Patent and making part of the same.

TO ALL WHOM IT MAY CONCERN:

Be it known that I, A. B. EDMANDS, of Melrose, in the county of Middlesex, and State of Massachusetts, have invented an Improved Water-Meter and Motor; and I do hereby declare that the following, taken in connection with the drawings which accompany and form part of this specification, is a description of my invention sufficient to enable those skilled in the art to practise it.

My invention relates to the construction of that class of water-meters and motors employing rotary blades or valves, the improvement having particular reference to the construction and arrangement of the valves in connection with the mechanism for throwing them out against the inner surface of the meter-cylinder and in against the centre-shaft or drum to which they are hinged.

The drawing represents a water-meter or motor embodying my improvement.

A shows a cross-section of the same.

B, an end view of the valve-shaft and valves, the latter view showing the series of valve-blades closed against the centre-shaft, and in red lines their position thrown out from said shaft.

a denotes the meter or valve-case made cylindrical in form, and with tight heads screwed upon its ends.

Into one side of this meter-case opens the induction-pipe b, and from the opposite side leads the eduction-pipe c. Centrally within this case is a valve-support or drum, d, supported, by means of journals, e, at its opposite ends, in the cylinder-heads, the journals rotating freely in said heads.

Upon the outer surface of the shaft d are hinged flaps or valve-blades, f g h, which close down into pockets or recesses, i, in the outer surface of the valve-supporting drum, as seen at f, and swing from said drum out against the inner surface of the cylinder, as seen at g h.

When the valves or flaps are closed against the drum or shaft d, their outer surfaces are cylindric with the outer surfaces of the portions of the drum between the blades, as seen at B and at f. Above the inlet-pipe b is an abutment or stationary wall, k, and this wall, the valve g, on the opposite side of the inlet-pipe, and the surfaces of the drum and meter-cylinder embraced between them, form the water-receiving chamber or compartment for the supply of water from the pipe b.

The pressure of the water thus entering the chamber against the valve g, drives said valve rotatively until the outer edge of the next valve or flap f passes by the abutment k, (with which each valve edge makes a practically impervious joint,) when said valve f will be forced outward, (by positive means,) and its edge shutting against the surface of the cylinder, and passing the top of the inlet-pipe, the water will rush through the inlet-pipe, back of valve f, and its pressure against this valve will continue the rotation of the drum and its valves. While the chamber between valve f and wall k is filling, the rotation of valve g will carry its outer edge beyond the lower portion of outlet c, and the water will, by progression of valve f, be driven out through said pipe.

As valve g passes beyond the pipe c, it strikes a cam or incline, l, which throws it down against the drum into its recess or pocket, i, and while so closed, the outer edge of the third valve h passes by edge of wall k, and is thrown out, to form between it and wall k, the water-receiving chamber or bucket, so that as water is thus received into and fills each chamber under pressure, and by rotation of the chamber thus formed is discharged, it will be seen that by projecting one of the journals, e, beyond the case, and connecting therewith an index-mechanism, the delivery of water may be accurately measured, or that by gearing from said journal the rotary movement of the drum may be transmitted to other mechanism, the water-driven shaft being thus used as a motor.

Now, to carry each valve-blade or flap in succession from its closed position in its pocket to a position to form a partition from the shaft to the surface of the cylinder, or a piston, upon which the pressure of the water shall act to rotate the shaft, I construct the valves and operate them as follows:

At one end of the valve-supporting drum e, I cut away from the surface of the drum toward the journal, so as to form circular recesses, l, and projecting from each hinge-pin, m, on the side opposite the valve, I form integral with each valve a tail-piece or extension, x, which, as the valve turns on its hinge, swings round in the

recess *l*, its inner surface matching with or playing accurately upon the circular surface of the recess. In the end of this tail-piece I make a cam-groove, *n*, closed at one end and open at the other, as seen at B. Across each bridge, *o*, left in cutting out the recesses *l*, I also form a groove, *p*, and into the opposite ends of each groove, *p*, the two cam-grooves *n*, on opposite ends of it, enter, when the two extensions having such grooves are both thrown round against the bridge, one valve being in such case open and the other closed.

Projecting inward from the head of the cylinder *a*, in the path of rotation of the grooves *p*, is a stationary pin, *r*, located in such position relatively to the edge of the wall or abutment, that as soon as the swinging edge of a valve or flap, *f*, for instance, passes this wall, the pin passes from groove *p*, next to valve *f*, into groove *n* of said valve, said groove being, when closed, in communication with said groove, *n*, of valve *f*.

Groove *n* is eccentric to pin *r*, and as drum rotates the pin *r*, to maintain its position, has, in moving through groove *n*, to swing such groove round, thereby swinging out the valve or flap until its edge comes against the inner surface of the cylinder, or rather until its jointed edge comes against a shoulder, *s*, of the drum. When thus brought to a stop, the change of position of the valve will have carried the groove *n* from the groove *p*, with which it last communicated, to the next groove *p*, in the next bridge, so that as drum rotates, the pin will pass out of groove *n* into said groove *p*, from which it will next pass into groove of valve *g*, causing such valve to be swung out, as was valve *f*, and will then pass from said groove *n* into groove *p* of next bridge, thence into groove *n* of valve *h*, and so on, the grooves being thus worked in continuation as though but one continuous groove.

By this means the motion of each valve is made positive in assuming position to be acted upon as a piston by pressure of the water, while it is left free from action of the pin as soon as it closes against the surface of the meter-case, and is then acted upon only by the pressure of the water until it passes the outlet, and is closed against the drum by the incline.

It will thus be seen that the construction is very simple and inexpensive, not subject to great wear or strain, and constructed to act with accuracy in determining the amount of water flowing into and through the meter under pressure.

I claim a water-meter or motor, made with valve-blades or flaps, hinged to and swinging against and from an axial drum, such blades being rotated by pressure of the water entering the meter-case through the eduction-pipe, and each valve-blade being thrown out from the drum as its outer edge passes the abutment or wall, substantially as set forth.

A. B. EDMANDS.
